UNITED STATES PATENT OFFICE.

JOHN HERGESHEIMER, OF GLENSIDE, PENNSYLVANIA, ASSIGNOR TO THE CURTIS PUBLISHING COMPANY, OF PHILADELPHIA, PENNSYLVANIA, A CORPORATION OF PENNSYLVANIA.

STOP-MOTION FOR STENCIL-CARD-FEED ADDRESSING-MACHINES.

1,180,645.

Specification of Letters Patent. Patented Apr. 25, 1916.

Application filed March 3, 1915. Serial No. 11,736.

To all whom it may concern:

Be it known that I, JOHN HERGESHEIMER, a citizen of the United States, and a resident of Glenside, in the county of Montgomery and State of Pennsylvania, have invented a certain new and useful Stop-Motion for Stencil-Card-Feed Addressing-Machines, of which the following is a specification.

In addressing machines of the type to which the attachment or stop motion of this invention is applicable, the paper feed and the printing head operate continuously as long as the machine is running, and in feeding the stencil cards one on-coming card is relied upon to push onward the stencil card that is under the printing head. It sometimes happens that the feed fails so that the oncoming card is delayed and a card remains under the printing head during a repetition of the printing operation. In consequence of this the address is repeated on the paper and this may lead to great confusion or duplication.

The principal objects of the present invention are to avoid the above mentioned defects and disadvantages and to provide for automatically stopping the machine in the event of failure of the stencil card feed and in the event of the absence of stencil cards for any other reason, such as oversight or neglect on the part of the attendant.

The invention will be claimed at the end hereof, but will be first described in connection with the embodiment of it chosen from other embodiments for the sake of illustration in the accompanying drawings, in which—

Figure 1, is a top view of an addressing machine, or parts thereof, provided with a stop motion mechanism embodying or containing the invention. Fig. 2, is a front view of the same. Fig. 3, is a transverse sectional view of the same. Fig. 4, is a diagrammatic view, partly in section, illustrating stop motion mechanism embodying features of the invention, and Fig. 5, is a perspective view of a stencil card.

In the drawings 1 is a reciprocating actuator, 2 is a controller and there are yielding means interposed between the actuator and controller whereby the controller is op-

erated by the actuator in the absence of a stencil card. To facilitate the description, reference will be made to the addressing machine illustrated in the drawings, although it is not intended to confine the invention to that particular construction of addressing machine.

The actuator 1 is shown as applied to the printing head 3 which is rocked by a cam mechanism 4 carried by the drive shaft 6 having a pulley 7. The controller 2 is arranged to contact with one of the stencil cards α . As shown in the particular machine illustrated the controller does this by working through an opening in the top one of the guides 8 along which the stencil cards are fed by one pushing another to the printing head 3. The stencil cards are fed from a hopper 9 by a pawl 10 which engages the frame 11 of a stencil card. The spring pawl 10 is driven by the links 12 and crank-arm 13, which in its turn is driven by the bevel gears 14 from the shaft 6. The pawl operates intermittently so as to push the bottom card out of the hopper and then when the next card is pushed out of the hopper it pushes the first mentioned card toward the printing head 3. It will therefore be seen that one card is relied upon to push another card away from the printing head after the printing has been done. 15 and 16 are strips of paper that are positively fed in respect to the cards. The paper feed is or may be driven from the shaft 6, although the mechanism is not shown for doing it but the mechanism is well understood by those skilled in the art. Two strips, 15 and 16, of paper are shown because in the machine chosen for illustration duplicate strips are made.

With this explanation a further description will be given of the details of the stop motion mechanism.

17 is a block mounted upon the frame of the machine and bored for the accommodation of the controller 2 and for the cap 18 of insulating material fitted so as to slide telescopicallly on the controller 2. The block is mortised for the accommodation of contacts 19.

20 is a guide pin working in a slot in the block.

The cap 18 is in range of the actuator 1 and between it and the controller there is interposed a comparatively strong spring 21. The controller is shown in the form of 5 a plunger with a stem 22 of reduced cross-section that extends down through the opening in the top guide 8 so as to rest and ride upon a card α traveling in the guides. Around the stem and under the plunger 10 body of the controller 2 there is a comparatively light spring 23.

The operation of the stop motion mechanism may be described as follows: Every 15 time a printing operation takes place the actuator 1 is reciprocated. If there is a stencil card under the stem 22 the controller remains at rest, the cap 18 descends compressing the spring 21. If there is no card under the controller and the actuator descends, the spring 21 being stronger than 20 the spring 23 compresses the latter and drives the plunger body of the controller downward into contact with the contacts 19. Thus the contacts 19 and the controller may 25 constitute a switch or make-and-break device that may be used to control an electric circuit which in its turn may be employed in a variety of ways to prevent further operation of the machine. As shown the contacts 19 are interposed in a circuit 24 which 30 constitutes a shunt by means of which the holding coil 25 of the starting box 26 can be cut out of circuit. Of course when the starting coil 25 is cut out of circuit the arm 26 α is moved by its spring into the position 35 shown in the drawings, in which the motor circuit 27 is interrupted so that the motor 28 stops. The motor 28 drives the pulley 7, or at any rate operates the working parts, 40 or some of them, of the addressing machine, so that when the motor stops the printing operation is interrupted. As the printing head 3 is descending to printing position 45 the actuator strikes the cap 18. If a card is under the stem 22, the stop motion mechanism remains in its normal inactive position but if the feed mechanism has failed to push out the bottom card from the hopper it catches the card then under the lower 50 end of the stem 22 and pushes it away so that when the actuator 1 and printing head descend, the stop motion mechanism becomes active.

It will be obvious to those skilled in the 55 art to which the invention relates that modifications may be made in details of construction and arrangement and that the stop motion mechanism can be applied to addressing machines other than the one illustrated 60 in the drawings without departing from the spirit of the invention hence the latter is not limited as to those matters or in any way other than as the appended claims and the prior state of the art may require.

What I claim is:

1. A stop motion mechanism for stencil card addressing machines comprising the combination of a continuously reciprocating actuator continuously operating a part of a plunger mechanism, electric contacts, and a plunger mechanism coöperating with said electrical contacts and whose motion in respect thereto is arrested by a stencil card. 65 70

2. A stop motion mechanism for stencil card addressing machines comprising the combination of a reciprocating actuator, two elements in movable relation having a spring interposed between them and whereof one is continually operated by the actuator and whereof the other is actuated only 75 80 in the absence of a stencil card, and a spring support for the last mentioned element so that it remains inactive in the absence of a stencil card.

3. A stop motion mechanism for stencil card addressing machines comprising the combination of a reciprocating actuator, two elements in movable relation having a spring interposed between them and whereof one is continually operated by the actuator and whereof the other is actuated only 85 90 in the absence of a stencil card, a spring support for the last mentioned element so that it remains inactive in the absence of a stencil card, and switch contacts controlled 95 by the last mentioned element.

4. A stop motion mechanism for stencil card addressing machines comprising the combination of a reciprocating actuator, a spring supported plunger with card space 100 beneath it, a head telescopically and springingly mounted on the plunger and disposed in range of the actuator, and stop mechanism controlled by the plunger.

5. A stop motion mechanism for stencil card addressing machines comprising the combination of a reciprocating actuator tending to operate a controller, a normally inactive controller adapted to contact with a stencil card, and yielding means interposed between the actuator and controller, whereby the controller is actuated in the absence of a card and is not actuated in the presence of a card. 105 110

6. A stop motion mechanism for stencil card addressing machines comprising the combination of means for normally making a controller inactive, an actuator having yielding relation to the controller and tending to overcome said means and operate the 115 controller, and a controller adapted to contact with a card and operative in the absence and inoperative in the presence of a card.

7. A stop motion mechanism for stencil card addressing machines comprising the combination of a reciprocating actuator, a block bored and mortised, electrical con- 120 125

tacts arranged in the spaces of the mortises, a spring supported plunger, and an insulating cap in sliding relation with the plunger arranged in the space or bore of the block; 5 a spring interposed between the plunger and cap, and a projecting stem on the plunger, substantially as described.

In testimony whereof I have hereunto signed my name in the presence of two witnesses.

JOHN HERGESHEIMER.
